UNITED STATES PATENT OFFICE.

JAMES A. SINCLAIR, OF WOODSFIELD, OHIO, ASSIGNOR TO HIMSELF AND
WARREN HOLLISTER, OF SAME PLACE.

IMPROVEMENT IN PUMPS.

Specification forming part of Letters Patent No. 131,169, dated September 17, 1872.

To all whom it may concern:

Be it known that I, JAMES A. SINCLAIR, of Woodsfield, in the county of Monroe and State of Ohio, have invented an Improved Pump, of which the following is a specification:

The invention will first be fully described and then clearly pointed out in the claim.

Figure 1 is a vertical, central, and sectional elevation of my improved pump. Figs. 2 and 3 are detail views of the valve-plates.

A in the drawing represents a case or shell, having body *a* and bottom *a'*, of iron, which are cast in a single piece. B is an inner cylinder, open at both ends, and made of glass or metal, preferably in one or more longitudinal sections, to allow for expansion and contraction. C is an intermediate cylinder, formed of cement. The cement forms a water-tight joint between the shell A and inner cylinder B, while its elasticity admits of the said contraction and expansion without producing a leak. By this construction I avoid all seams and joints, and form a pump-cylinder which is not comparatively but absolutely water-tight. D is the piston-rod, which is rigidly attached to a double collar, *d* *d'*, the part *d'* sliding upon the guide-tube *d''*. E is a pipe, extending from cylinder A B C, and enlarged at the end to re-

ceive upwardly-opening check-valve *e*. F is the piston, which is provided with a cast-metal and apertured plate, *f*, and a leather valve, *f'*, which may be adjusted with respect to one another.

It will thus be perceived that the inner cylinder, being in sections, can readily expand, while the cement forms a water-tight inclosure which prevents the liquid from coming in contact with the cast-iron outer cylinder.

This mode of forming a pump-cylinder is intended as an improvement over that shown in patent granted to me on the 6th of June, 1871.

Having thus described all that is necessary to a full understanding of my invention, what I esteem to be new, and desire to protect by Letters Patent, is—

A pump-cylinder, consisting of an inner cylinder in longitudinal sections, a cement-cylinder adjacent thereto, and an outer cast-iron cylinder in one piece, all applied together as described.

JAMES A. SINCLAIR.
